(57) **CLAIM**

(21) Appl. No.: **29/135,368**

The ornamental design for a multi-brush ultrasonic nail cleaner, as shown and described.

(22) Filed: **Jan. 11, 2001**

DESCRIPTION

(51) LOC (7) Cl. **04-02**

FIG. 1 is a left side, front and top, isometric view of a multi-brush ultrasonic nail cleaner showing my new design, the exploded broken line portion of FIG. 1 being intended to illustrate the environment in which the design is sometimes associated, and being for illustrative purposes only, forming no part of the claimed design or a specified embodiment thereof;

(52) U.S. Cl. **D4/100**; D4/120

FIG. 2 is a top plan view thereof;

(58) Field of Search D4/100, 119, 120,

FIG. 3 is a left side, elevational view thereof;

D4/121, 127, 130; 15/21.1, 106, 113, 159.1,

FIG. 4 is a front elevational view thereof;

160, 167.1, 167.3, 186, 187, 191.1

FIG. 5 is a right side elevational view thereof;

(56) **References Cited**

FIG. 6 is a rear elevational view thereof; and,
